Patented Nov. 29, 1921.

FIG. 1.

FIG. 2.

FIG. 3.

FIG. 5.

Paul Lux
An O' Bright, Attorney

UNITED STATES PATENT OFFICE.

PAUL LUX, OF WATERBURY, CONNECTICUT, ASSIGNOR TO LUX CLOCK MANUFACTURING COMPANY, INC., OF WATERBURY, CONNECTICUT, A CORPORATION OF CONNECTICUT.

CLOCK-FRAME.

1,398,597.

Specification of Letters Patent. Patented Nov. 29, 1921.

Application filed August 25, 1921. Serial No. 495,284.

To all whom it may concern:

Be it known that I, PAUL LUX, a citizen of the United States, residing at Waterbury, in the county of New Haven and State of Connecticut, have invented certain new and useful Improvements in Clock-Frames, of which the following is a specification, reference being had therein to the accompanying drawing.

10 This invention relates to certain new and useful improvements in clock frames and more particularly to means for securing the back frame to the pillars, the object being to provide a construction of clock frame 15 which can be quickly assembled.

Another and further object of the invention is to provide a novel form of pillar which is stamped out of sheet metal having a pair of lugs at one end adapted to pass 20 through spaced openings in the back frame and be spread by a spreading tool so as to securely fasten the back frame to the pillars.

A still further object of the invention is to provide a novel means for securing the 25 main spring to the pillar by providing the end of the main spring with an elliptical shaped opening instead of a loop and one of the pillars with a lug offset therefrom over which is adapted to be placed the end 30 of the spring in such a manner that the tension of the main spring will hold it in place, whereby a broken main spring can be readily replaced in the clock without taking the clock apart, as it is simply necessary to unhook the broken portion from the pillar and from the main arbor and rewind a new 35 spring on the main arbor with the clock winding key and hook the free end of the spring over the hook on the pillar.

40 A still further object of the invention is to provide a clock frame in which the structural strength is increased by locating the pillars at various angles for if the plane of the pillars were parallel with the frame of 45 the clock, it would have a tendency to bend in the direction at right angles to the plane of the pillars. By placing the pillars at various angles a rigid frame is formed.

Other and further objects and advantages 50 of the invention will be hereinafter set forth and the novel features thereof defined by the appended claims.

In the drawings,

Figure 1 is a plan view of a clock frame

constructed in accordance with my invention;

Fig. 2 is an elevation of the same, partly in section;

Fig. 3 is a plan view of the back frame;

Fig. 4 is a perspective view of the pillar 60 having the lug to receive the end of the main spring of the clock; and

Fig. 5 is a perspective view of a slightly modified form showing the shoulder headed rivet secured to the pillar over which the 65 end of the main spring is adapted to be hooked.

In constructing a clock frame in accordance with my invention I employ a front frame 1 and a back frame 2, the front being 70 provided with openings 3 through which the reduced portions 4 of flat pillars 5 are adapted to extend and be riveted as shown at 6. These pillars are preferably stamped of sheet metal and are arranged at an angle 75 to the edges of the clock as shown in order to increase the structural strength of the frame. The other ends of the pillars are provided with spaced lugs 7 which are adapted to pass through spaced openings 8 80 in the back frame 2 and spread as clearly shown with a wedge-shaped spreading tool so as to securely fasten the back frame on the pillars.

One or more of the pillars in constructing 85 a clock frame are provided with offset lugs 9 which are adapted to receive the ends of the springs 10 and 11. The free ends of these springs are provided with elliptical shaped openings 10' and 11' through which 90 are adapted to pass the lugs 9 for fastening the free ends of the springs to the pillars in such a manner that when one of the springs becomes broken, the old one can be 95 readily removed and a new one inserted.

When it is desired to insert a new main spring, one end of the spring is hooked over the main arbor and the spring is wound thereon with the winding key and when the clock is almost fully wound up, the end is 100 forced over the lug of the pillar and by continuously winding the spring the proper tension will hold the spring in position at all times and while I have shown this construction in use for holding both of the 105 springs in the clock frame, of course, I do not wish to limit myself to the use of any particular number of pillars constructed

with lugs to receive the end of a clock spring in constructing the main frame of a clock, as my invention consists broadly in forming a flat pillar for a clock frame with a 5 lug over which the end of the spring of the clock is placed and secured by the tension of the spring in such a manner that an old spring can be readily removed and a 10 new one inserted without taking the frame 10 apart.

In the modification shown in Fig. 5 I have secured a shoulder rivet 12 provided with a head in an opening formed in the pillar 13 over which the end of the spring is 15 placed, as I am aware that instead of forming the lug integral with the pillar it could be formed separate and the same result obtained and therefore I do not wish to limit myself to the forming of a flat pillar with 20 an integral lug to hold the spring.

From the foregoing description it will be seen that I have provided a clock frame formed of a pair of frames connected together by flat pillars arranged at various 25 angles so as to increase the structural strength of the frame, said pillars being secured to the front frame in a novel manner in order to allow the back frame to be readily attached, one or more of the pillars 30 being provided with a lug to receive and hold the end of the spring in such a manner that the spring can be readily inserted or removed.

I have found in practice that preferably 35 sheet metal is used for forming the pillars but it is, of course, understood that any other suitable material can be used and therefore I do not wish to limit myself to the use of any particular kind of material in forming 40 the pillars.

I have described the pillars being fixed to the front frame and detachably secured to the back frame of the clock, but it is, of course, understood that in constructing some 45 kinds of clock frames the pillars could be

secured to the back frame and detachably secured to the front frame and in fact, I do not wish to limit myself to the securing of the pillars to the frame by forming one end of the pillars in a particular manner as I 50 am aware that both ends of the pillars could be formed with spaced lugs and secured to the respective frames.

While I have shown and illustrated certain details of construction I do not wish 55 to limit myself to these details of construction as my invention consists broadly in constructing a clock frame with flat pillars detachably connected to one of the frame members having a lug or hook adapted to 60 pass through an opening formed in the end of the spring for holding the spring within the clock frame in such a manner that it can be readily detached for removing a broken spring and inserting a new spring. 65

What I claim is:—

1. A clock frame formed of front and back frames, flat pillars carried by the front frame having spaced lugs at their ends, the back frame being provided with spaced 70 openings to receive said lugs, said lugs being adapted to be spread apart for fastening the back frame thereto.

2. A clock frame formed of front and back frames, the front frame being provided with 75 slots and the back frame with spaced openings, flat pillars having one of their ends secured within the slots of the front frame by riveting the ends of the pillars, said pillars having spaced lugs at their other ends 80 extending through the spaced openings of the back frame and secured therein by spreading the lugs.

3. A pillar for clocks stamped out of sheet metal to form a flat pillar having spaced 85 lugs at one end.

In testimony whereof I hereunto affix my signature.

PAUL LUX.
